UNITED STATES PATENT OFFICE.

WILLIAM J. McCACKEN, OF SIOUX CITY, IOWA.

TILE-MAKING MACHINE.

1,200,633.

Specification of Letters Patent. Patented Oct. 10, 1916.

Application filed August 31, 1910. Serial No. 579,812.

To all whom it may concern:

Be it known that I, WILLIAM J. McCACKEN, a citizen of the United States, residing at Sioux City, in the county of 5 Woodbury and State of Iowa, have invented certain new and useful Improvements in Tile-Making Machines; and I do hereby declare the following to be a full, clear, and exact description of the invention, such as 10 will enable others skilled in the art to which it appertains to make and use the same.

This invention relates to improvements in tile making machines, and particularly to machines for compressing a tile in a mold 15 by a rotary motion of a former.

The object in view is the arrangement in a tile making machine, of means for guiding material into a mold, associated with means for lowering, raising, and rotating a former 20 in the mold for packing and smoothing the tile.

Another object of the invention is the arrangement in a tile making machine, of a mold associated with means for guiding 25 material thereto, and a former arranged to operate therein, and a walking beam arranged to raise and lower the former, the walking beam being formed in such a manner as to hold the former at the bottom of 30 the mold for a short time notwithstanding that the power applied to the walking beam is continuous.

A still further object of the invention is the arrangement in a tile making machine of 35 a walking beam arranged with a slot therein for accommodating a pin, whereby the walking beam may raise and lower a former associated with the walking beam, the slot in the walking beam being formed so as to 40 hold the former at its lowermost position for a short time upon forming each tile, the walking beam and associated parts being arranged to operate in connection with means for continuously rotating a former.

With these and other objects in view the 45 invention comprises certain novel constructions, combinations and arrangement of parts as will be hereinafter more fully described and claimed.

In the accompanying drawings:—Figure 50 1 is a side elevation of an embodiment of the invention. Fig. 2 is a front view of the structure shown in Fig. 1. Fig. 3 is a top plan view of the structure shown in Fig. 1. Fig. 4 is a fragmentary sectional view 55

through Fig. 2 on line 4—4. Fig. 5 is a fragmentary sectional view taken approximately on line 5—5 of Fig. 4. Fig. 6 is a detail view of the walking beam.

In constructing a tile making machine 60 embodying the invention a suitable framework of any desired kind is provided for holding the various moving parts properly in position. Rotatably mounted in this framework is a former shaft preferably constructed square so as to freely receive power from a power transmitting means mounted on the frame, which power transmitting means in turn receives power from any suitable source, a clutch being used for throwing on and off power. Connected with the former shaft is a former of any desired kind designed to be raised and lowered by the former shaft, and rotated at the same time so that the former will thoroughly pack 65 and smooth the tile as it passes through the mold. The power transmitting means may consist of any desired means, that shown being a pulley which is rotated, and consequently rotates the former shaft regardless of any vertical movement of said shaft. In order to properly raise and lower the former an operating or radius bar is pivotally mounted on the framework of the machine, and connected with the former shaft 70 and with the power transmitting means so that whenever the power is turned on for 75 raising the former shaft the same will be raised and lowered properly for moving the former into and out of the mold while the same is being rotated.

In order that the invention may be more clearly understood an embodiment of the same is shown in the accompanying drawings, in which 1 indicates the framework, 95 and 2 the former shaft, which is preferably constructed square in cross section. A power shaft 3 is provided which has loosely mounted thereon a power pulley 4 designed to receive power from any suitable source, 100 and to transmit the power to shaft 3, through a suitable clutch 5. Shaft 3 has rigidly secured thereto a power transmitting pulley 6 which transmits power to belt 7 passing over idlers 8—8, and from thence 105 around driving pulley 9. Driving pulley 9 is located between bearings 10 and 11 so as not to be allowed any vertical movement. In order that the driving pulley 9 may properly transmit power to former shaft 2 the pulley 110

is provided with a square aperture for snugly fitting the square shaft 2, but sufficiently loose to permit a free up and down or reciprocatory movement of the shaft. By 5 this construction and arrangement of power transmitting means, former shaft 2 is rotated whenever power is turned on to the machine by clutch 5. At the same time that power is turned on for rotating former shaft 10 2 power is also transmitted to means for reciprocating shaft 2, so as to move the former 12 into and out of mold 13. These means comprise a worm 14 rigidly secured to power shaft 3, and meshing with worm 15 gear 15 for properly rotating the same.

Gear 15 is rotatably mounted on shaft 16 supported on the framework 1 by a suitable bracket 17. Pivotaly connected at 18 to gear 15 is a link 19 which is also pivoted at 20 20 to a bracket 21 connected with radius bar 22. The radius bar 22 is formed preferably of two bars so as to straddle bearing block 23. The radius bar 22 is pivotally mounted at 24 in brackets which in turn are rigidly secured to framework 1. By this structure whenever gear wheel 15 makes a complete revolution radius bar 22 moves down and then up, making a complete cycle for moving former 12 into and then again out of mold 30 13. Each of the bars comprising radius bar 22 is provided with a slot 25 extending in the same general direction as the radius bar 22 for part of the distance, and then turning at an angle at 26 so that when the radius bar 35 reaches substantially its lowermost position the continued movement of gear 15 will not cause any movement of former shaft 2, so that the former 12 may rotate a short time at the bottom of mold 13. In order to accomplish this the pins 27 and 28, which are rigidly secured to bearing member 23, extend through slots 25 and ride up into the curved portion 26 just before the walking beam reaches its lowermost position. This structure is provided so that the bottom of the tile will be formed as perfectly as the remaining parts. If the former did not remain a short time at the bottom of the mold 40 a short section of the tile would not receive the packing and smoothing which the remaining parts receive, and consequently produce an inferior tile. The bearing member 23 (Figs. 4 and 5) is provided with an annular socket 29 for receiving stop 30. The 45 stop 30 is rigidly secured to former shaft 2 by suitable set screws, but bearing member 23 is loosely mounted upon the shaft and has stop 30 loosely journaled therein so that the shaft may freely rotate and yet bearing member 23 remain stationary. The function 50 of bearing member 23 is to raise former shaft 2. The former shaft 2 is moved downward under the action of gravity when not 55 positively prevented by bearing member 23, though if desired a bearing member, similar

to bearing member 23, could be placed above stop 30, and the former shaft 2 forced positively in both directions.

Arranged above mold 13 is a guiding chute or hopper 31 which is arranged to fit 70 over or against the mold 13 so as to guide cement or other material into the mold. A pair of brackets 32 and 33 are rigidly secured to hopper 31 for holding the hopper properly in position. Passing through 75 brackets 32 and 33 are guiding rods 34 and 35 which guide the hopper in its reciprocatory movement. Surrounding rods 34 and 35 are springs 36 and 37 which bear at one end against brackets 32 and 33, and at the 80 other against adjustable stops 38 and 39. The rods 34 and 35 are held rigidly in position in suitable brackets, which brackets are secured to framework 1. Springs 36 and 37 normally press downward on hopper 31 for 85 holding the same tightly against a mold placed therein. In order to remove the mold it is necessary to raise hopper 31, which is done automatically by movement of rods 40 and 41 which are rigidly secured to the 90 hopper, and are adjustably secured to a yoke 42. Yoke 42 rests upon stop 30, and has an aperture 43 for accommodating former shaft 2. Aperture 43 is of sufficient size to permit the free rotation of the former shaft 2 95 without interference. By this arrangement whenever radius bar 22 raises the former sufficiently high to be removed from the mold 13 the same will cause stop 30 to press against yoke 42 and convey power thereto 100 for raising automatically hopper 31 against the action of springs 36 and 37. The various parts of the machine are adjusted so that hopper 31 is raised when radius bar 22 reaches its highest position. It will be evident that the first movement downward of 105 radius bar 22 will permit hopper 31 to be lowered under the action of springs 36 and 37 so that the hopper 31 is in position for receiving cement or other material in proper 110 time for being packed or compressed into a tile by the former 12. In operation the cement or other material is not placed in the hopper until former 12 has reached its 115 lowermost position, or substantially its lowermost position.

What I claim is:

1. In a tile-making machine, the combination of a frame-work, a former arranged to compress a tile in a suitable mold, a shaft 120 for operating said former, means for rotating said shaft, a walking beam having a loose connection with said shaft for moving the same vertically during the rotation thereof, and designed to hold the former a 125 short time against vertical movement at its lowermost stroke, means for operating said walking beam, a hopper for guiding the material into the mold, a pair of rods connected to said hopper, a yoke carried by 130

- said rods, a stop on said shaft for engaging said yoke and raising the hopper out of contact with the mold when the tile has been formed, and resilient means for lowering said hopper when said stop is lowered. 5
2. In a tile making machine, the combination of a frame, a vertical shaft slidably mounted on said frame, a former secured to the lower end of said shaft for operating 10 in a suitable mold, means for rotating said shaft and means for automatically raising and lowering said shaft without interrupting the rotation thereof, said means including a walking beam provided with a curved 15 slot at its front end and a connection between said shaft and said curved slot the curvature of said slot being such that vertical movement of the rotatable former is automatically delayed for a short time when 20 the former is at the bottom of the mold notwithstanding the continuous operation of the walking beam and shaft, whereby the bottom of the tile is formed as firmly and smoothly as the remaining portion. 25
3. In a tile-making machine, the combination of a frame-work, a vertical shaft mounted thereon, a former fixed to the lower end of said shaft for operating in a suitable mold, means for rotating said shaft, means 30 for lowering said shaft, holding the same a short time at its lowermost position and again raising the same without interrupting the rotation thereof, a vertically reciprocable hopper for guiding the material
- into the mold, a pair of rods connected to 35 said hopper, a yoke carried by said rods, a stop on said shaft for engaging said yoke and raising the hopper out of contact with the mold when the shaft has risen to a pre-determined position, and resilient means for 40 lowering said hopper when said stop is lowered. 4. In a tile making machine, the combination of the frame work, a vertical shaft mounted thereon, a former fixed to the lower 45 end of said shaft for operating in a suitable mold, means for rotating said shaft, a stop carried by said shaft, means operatively connected to said stop for reciprocating said shaft, a vertically reciprocal hopper for 50 guiding the material in the mold, a pair of brackets arranged diametrically opposite on said hopper, a pair of vertical rods carried by the frame-work and extending through said brackets, coil springs encircling said 55 rods, a yoke resting upon the stop carried by the said shaft, means of connecting the hopper with the said yoke whereby upon the upward stroke of the shaft the hopper will be raised and the said coil springs adapted 60 to lower the said hopper when the stop is lowered.

In testimony whereof I affix my signature in presence of two witnesses.
